ATTORNEY

UNITED STATES PATENT OFFICE.

ARTHUR J. CLARK, OF BATH, MICHIGAN.

FUNNEL.

1,323,154.

Specification of Letters Patent. Patented Nov. 25, 1919.

Application filed October 7, 1916. Serial No. 124,376.

To all whom it may concern:

Be it known that I, ARTHUR J. CLARK, a citizen of the United States, residing at Bath, in the county of Clinton and State 5 of Michigan, have invented certain new and useful Improvements in Funnels, of which the following is a specification.

This invention relates to funnels and the object of the same is to provide an improved 10 funnel that will automatically cut off the flow of liquid therethrough when the same reaches a predetermined height in the vessel being filled.

Another object of this invention resides 15 in the production of an improved funnel of the type above set forth in which means is provided for carrying the same, the said means being attached to the cut-off device and therefore when the funnel is trans- 20 ported with liquid therein, there is absolutely no likelihood of the same passing through the funnel.

A still further object of this invention re- 25 sides in the production of a device of the kind above described, that is simple in construction, efficient in operation, consists of the minimum number of parts and can be manufactured for the minimum amount.

With these and other objects in view, this 30 invention consists of certain novel constructions, combinations and arrangement of parts, as will be hereinafter fully described and claimed.

In the accompanying drawings, a vertical 35 sectional view of the device is shown.

Referring to the parts by reference numerals, the body of the funnel is designated by the numeral 10 and a pipe 11 closed at one end as at 12, is carried by the body 10 40 and has projecting therefrom a portion 13 forming a spout for the funnel. Adjacent the end of the funnel body 10 and the point of engagement of the pipe 11 with the body 10 is a vessel abutment pad 14, the same being 45 constructed of cork or rubber so that the funnel can be retained in connection with a receptacle being filled by means of the engagement of the pad 14 with the neck of the vessel. As is clearly shown in the drawing, 50 this pad encircles the funnel body 10 and also the pipe 11 and therefore retains the pipe 11 in the proper position in connection with the body 10.

A pair of openings 15 are formed in the 55 pipe 11 adjacent the lower extremity of the body 10 of the funnel, and a second pair of

apertures 16 are formed in the pipe 11, more specifically in that portion thereof that forms the spout 13. As is evident, the openings 15 are inlet openings and those designated by the numeral 16 are discharge openings. A sleeve 17 is secured fast to the inner face of the pipe 11 between the openings 15 and 16, the same having the inner face thereof of a curved contour for a purpose 60 to be hereinafter set forth. A float 18 is provided with this device, the same having secured thereto, an operating rod 19 that passes through an opening 20 in the closed end 12 of the pipe 11 and a hand grip 21 is 65 positioned on that portion of the rod 19 that projects beyond the upper face of the closed end 12 when the float 18 is in its lowermost position. The said float 18 is preferably 70 constructed of cork and has the upper portion thereof beveled as at 22 so as to snugly engage the rounded seat presented by the 75 sleeve 17.

It is to be understood that liquid normally passes from the body 10 through the 80 openings 15 into the pipe 11 and out through the discharge openings 16. However as the liquid rises in the vessel being filled, the float 18 of course moves toward the seat provided by the sleeve 17 and will 85 engage the sleeve and thus prevent the flow of liquid through the pipe 11. It will thus automatically cut off the flow of liquid into the receptacle being filled. It is also to be noted that the hand grip 21 will move up- 90 wardly as the liquid rises in the receptacle being filled and it can thus be judged as to the height of the liquid in the receptacle. Should the vessel being filled, be of such type as to make it inadvisable to allow the 95 float 18 to rise to such a height as to engage the sleeve 17, the flow of liquid can be cut off by manually moving the float 18 into engagement with the sleeve 17 by means of the grip 21 and rod 19. When liquid is in 100 the body 10 and it is wished to transport the funnel it is obvious that the funnel is carried by the grip 21 and thus by the weight of the liquid and the funnel, the float 18 will be somewhat "wedged" into the sleeve 105 17 and positively prevent the flow of liquid into the spout portion 13 of the pipe 11.

It is obvious that minor changes may be made in the form of construction of this invention without departing from the material part thereof. It is therefore not wished to confine the invention to the exact 110

form herein shown and described, but it is wished to include all such as properly come within the scope claimed.

I claim:

- 5 A funnel including the usual body equipped with a tube extending through its apex, the lower end of the tube serving as the funnel spout and having discharge openings therein, the upper end of the tube
10 having inlet openings and having its upper end closed, a collar mounted in the tube between the inlet and discharge openings and having its inner periphery bulged inwardly, a float movably mounted in the tube and

adapted for a wedge fit in said collar to 15 close communication through the tube, a rod connected to the float and movably arranged in the tube, and an enlargement formed on the upper end of the rod to limit inward movement of the float and to provide a handle by which the funnel may be carried.

In testimony whereof I affix my signature in presence of two witnesses.

ARTHUR J. CLARK.
